UNITED STATES PATENT OFFICE.

EDWARD REDDIX AND JACOB L. REDDIX, OF PRICHARD, ALABAMA.

SWITCH-THROWING DEVICE.

1,325,170.

Specification of Letters Patent. Patented Dec. 16, 1919.

Application filed August 19, 1918. Serial No. 250,616.

To all whom it may concern:

Be it known that we, EDWARD REDDIX and JACOB L. REDDIX, citizens of the United States, residing at Prichard, in the county 5 of Mobile, State of Alabama, have invented certain new and useful Improvements in Switch-Throwing Devices; and we do hereby declare the following to be a full, clear, and exact description of the invention, such 10 as will enable others skilled in the art to which it appertains to make and use the same.

This invention is an improvement in railway appliances and has particular reference 15 to a switch throwing or operating mechanism.

An object of the invention is to provide an improved mechanism actuated from a moving train or car to automatically throw a 20 switch as the same is approached from either direction and then automatically return the switch to its normal position after the train or car has passed from the main line onto the siding or vice versa.

25 Another object is to provide a mechanism operated by a device carried by the front portion of a train or car to open the switch, and operated by a device carried by the rear portion of the train or car to return the 30 switch to its former position.

The inventive idea involved is capable of receiving a variety of mechanical expressions one of which, for the purpose of illustrating the invention is shown in the accompanying drawing, wherein:

Figure 1 is a top plan view showing the invention applied to a main line and siding and the switch therefor.

Fig. 2 is a side elevation.

40 Fig. 3 is an enlarged detail of the main line switch operating mechanism.

Fig. 4 is a similar view of the train carried device for operating said mechanism.

Fig. 5 is an enlarged detail of the siding 45 switch operating mechanism.

Referring more particularly to the accompanying drawing in which like reference characters indicate similar parts, the numeral 5 indicates the tracks of the main line

50 and 6 those of the siding and 7 indicates the switch which is adapted to be automatically thrown in both directions by the mechanism which comprises the essential feature of the invention.

55 The switch arm 8 of the switch 7 has one end extended to one side of the main line 5

and is connected at said end to one end of a link 9 and a bell crank lever 10. Mounted upon a base 11 adjacent to and operated with the switch is a signaling semaphore or lamp 12 for indicating to the engineer of the train the position of the switch.

Arranged any suitable distance from the switch is a main line switch operating mechanism and a siding switch operating mechanism. The main line switch operating mechanism, comprises a base 14 secured along one of the tracks of the main line and having standards 15 in the upper end of which is journaled a transverse rock shaft 16. Secured to this rock shaft between the standard 15 are contact members 17 and 18 movable with the shaft and consisting of angularly disposed arms one of which is arranged at all times in a vertical position so as to be 75 engaged by a device carried by the train or car. Disposed on opposite sides of the base 14 are spring fingers 19 which are inwardly bowed at their upper ends 20 to receive therebetween and yieldably retain arm 80 17 or 18 in a horizontal position so as to prevent accidental movement thereof. Carried by the rock shaft 16 and disposed in alignment with one of the arms 18 is an extension 21 to the free end of which is pivoted 85 one end of an operating rod 22 which is of sufficient length to extend from the mechanism to a point adjacent the switch 7 where the other end of the rod is pivotally connected to the arm of the bell crank 10 90 opposite that to which the link 9 is connected.

The siding switch throwing mechanism comprises a base 23 having standards 24 in which a rock shaft 25 is journaled. Secured to this shaft is a contact member 26 comprising an angularly disposed arm 27 similar to the arm 18 and which move in the opposite direction to that of the arm 18. Carried by the shaft 25 and extending upwardly and outwardly with respect to the arm 27 is an extension 28 to which one end of an operating rod 29 is pivoted, the remaining end of the rod being pivoted to the bell crank 10.

In operation should a train desire to pass from the main line into the siding, a contact operating device, carried by the train, and which will be presently described in detail, is adjusted so as to engage the vertical arm 17, to cause it to assume a horizontal position and engage the coöperating spring

fingers 20. This movement of the contact 17 will exert a pull upon the rods 22 and 29 whereupon the bell crank 10 will move on its pivot and operate the switch so as to 5 open the siding. In view of the movement of the rod 29, the vertical arm of the contact 26 will be swung to a horizontal position. After the locomotive or car has passed the contact 27, the contact operating device 10 carried by said car or locomotive is withdrawn so that the first car will pass the contact 26 without engaging or disturbing it in any manner. The contact operating mechanism carried by the rear car is not swung 15 into its operative position until after it passes the contact 17. The contact member of the last car, then engages the vertical arm of the contact 27 and moves said arm in a direction away from the switch and at the 20 same time through the medium of the rods 22 and 29 moving the contact 17 to its former position, operating the switch so as to close the siding and leaving the main line open. Should the train desire to pass from the siding on to the main line, the above operation 25 is reversed.

The contact operating devices carried by the locomotive or front portion of the train is preferably mounted upon the pilot of an 30 engine and comprises a bell crank 30 mounted to swing in a horizontal plane at right angles to the train and having one of its arms 31 disposed so as to extend outwardly in a position to engage the vertical 35 arms of the contacts and rock the same. The other arm of the bell crank is pivoted to a link 32 which extends to a point adja-

cent the cab of the engine where it is connected to a lever 33 within the reach of the engineer or fireman so that either one may 40 adjust the lever to operate the contact. A similar contact arm is carried by the rear portion of the train.

From the above it will be readily seen that there has been provided a novel switch 45 throwing mechanism that can be operated regardless of the direction in which the train is moving, and one that can be operated at will by the engineer or fireman without stopping the train. 50

What is claimed is:

A switch operating mechanism comprising 55 a base adapted to be disposed along a track and having standards, extending therefrom, a rock shaft journaled in said standards, contact members movable with the rock shaft one of which is adapted to be engaged by an operating device carried by the train to adjust the contact member, an extension carried by said rock shaft, a rod 60 connecting said extension with said switch whereby to throw the same when the contact member is operated, and retaining devices disposed on opposite sides of said base for alternately and yieldably engaging the 65 arms of said contact device when the same is operated in either direction.

In testimony whereof, we affix our signatures, in the presence of two witnesses.

EDWARD REDDIX.
JACOB L. REDDIX.
